Primary Examiner — Cathy Anne MacCormac(74) *Attorney, Agent, or Firm* — Alston & Bird LLP(57) **CLAIM**

The ornamental design for a printer housing, as shown and described.

DESCRIPTION

FIG. 1 is a perspective view of a printer housing according to my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top elevation view thereof; and,

FIG. 7 is a bottom plan view thereof.

In the drawings, the claimed design is defined by the shaded surfaces. The broken lines immediately adjacent shaded surfaces represent boundaries of the claim and form no part thereof. The broken lines depict environment subject matter, are for illustrative purposes only and form no part of the claimed design.
